UNITED STATES PATENT OFFICE.

WALTER L. ROGERS, OF CHICAGO, ILLINOIS, ASSIGNOR TO LOOSE-WILES BISCUIT CO.,
OF CHICAGO, ILLINOIS, A CORPORATION OF ILLINOIS.

CARTON-TAPING MACHINE.

Application filed January 16, 1928. Serial No. 247,046.

This invention relates to a machine for applying gummed tape to cartons, particularly for securing covers to the cartons.

The main objects of this invention are 5 to provide an improved machine which quickly seals a gummed strip over the top end of a carton and holds it in place until the adhesive means become set; to provide a machine which is simple in construction, 10 efficient in operation and which is operated automatically when the cartons to be sealed are placed in position thereon.

An illustrative embodiment of this invention is shown in the accompanying 15 drawings in which:

Figure 1 is a view in front elevation of the improved machine.

Figure 2 is a view in elevation of the machine taken from the right of Figure 1.

The machine in general comprises a receiving table or platform for the cartons which are manually placed thereon. The moving of the cartons in such position on 20 such platform actuates a trigger which in turn engages a clutch with the operating mechanism. Movement of the operating mechanism first functions to supply a suitable length of moistened gummed tape 25 across the top side of the carton and then to lift the carton upwardly into a chute which is provided with brushes vertically disposed at its diametrically opposite sides for sticking the ends of the moistened tape 30 down against the sides of the cartons and holding such tape in position until the 35 gummed material thereon sets. Means are also provided for suitably discharging the cartons from the upper end of the chute 40 onto a trackway.

In the construction shown in the drawings, a supporting framework is provided comprising a pair of side frames 1 and 2, connected by suitable cross members 3 to 45 form a rectangular open framework.

The power means for operating the machine comprise an electric motor 4 driving a belt 5 which passes over the pulley wheel 6 of the motor and a belt-wheel 7 on a counter shaft 8 which is journaled on the side 50 frames 1 and 2. The counter shaft 8 is provided with a gear pinion 9 which meshes with a gear wheel 10. The gear 10 is intermittently connected to a main shaft 11 by 55 a clutch 12 of suitable standard construc-

tion which maintains such connection for one revolution only, of the shaft.

The clutch 12 is caused to function so as to connect the gear 10 to shaft 11 by a rod 13 pivoted to one arm of the bell crank 14. The other arm of the bell crank 14 is connected by a link 15 to a rocker arm 16 pivotally mounted at 17 to side frame 2. The upper end of the arm 16 has a trigger 18 rigidly fastened thereto, the upper end 19 of which is in position to be engaged and rocked to the right, as viewed in Figure 2, by a carton 20 when said carton is manually moved into position on receiving platform 21.

Engagement of the clutch 12 rotates 11 upon which is keyed various operating elements. The first operation to take place upon the rotation of the shaft 11 is for the purpose of supplying moistened gummed tape across the top of the cartons placed in the machine. This is accomplished by a cam wheel 22, keyed on shaft 11 which actuates a roller 23 mounted on the middle portion of a link 24. The lower end of link 24 is 25 pivotally mounted on a bearing stud 25, rigidly mounted in a bracket 26 which with the bearing member 27 helps to support shaft 11. The upper end of link 24 is bifurcated and pivotally pinned to one end of a link 28 which has its other end pivoted to the medial portion of a link 29. The lower end of link 29 is pivotally connected to an arm 30 which in turn is pivotally mounted in supporting framework. The 35 upper end of link 29 rests on a carriage 31 which is slidably mounted on an inclined chute 32.

The chute 32 supports a gummed tape strip 33 which is supplied from a roll 34 40 in box 35. The carriage 31 for feeding tape 33 is of standard construction and the details are not essential to this invention as any standard form of tape-feeding mechanism may be used. As the tape passes 45 down the chute 32, it passes over an up-standing brush 36 mounted in a receptacle 37 adapted to contain a supply of water so as to moisten the gummed surface of the tape as it passes over said brush.

A suitable hinged pressing arm 38 is provided for holding the tape in contact with the brush 36 as it passes thereover. Movement of the tape-feeding mechanism is arranged to supply a length of moistened tape 50

which extends across the top of the carton, as shown in Figure 1, and projects a suitable distance from the opposite side thereof.

The next movement in sequence of operation is to sever the length of moistened tape at the same time that the receiving platform lifts the carton upwardly. Movement upwardly of the receiving platform 21 is accomplished by a crank arm 39, keyed to shaft 11 at one end, having its other end pivotally connected to the lower end of a pitman 40. The upper end of pitman 40 is provided with a slot 41 which embraces a bearing stud or pin 42 secured to a collar 43 that is rigidly mounted on a vertical table lifting shaft 44. A bearing 45, formed in the end of a rigid arm 46, carried on side frames 2, is provided for holding the lower end of the shaft 44 in vertical position in conjunction with the upper end of the shaft which is rigidly mounted on the under side of the receiving and lifting table 21. The upper end of shaft 44, underneath table 21, also carries a cross-head 47, rigidly mounted thereon, the ends of which ride in guideways 48 and 49 for guiding the table 21 in a vertical direction when lifted upwardly. The slot 41 in the upper end of pitman 40 permits the table and carton supported thereon to remain stationary during the operation of the tape-feeding mechanism, so that upward movement thereof is not commenced until after a suitable length of tape has been fed into position over the top of the carton.

35 The collar 43 is provided with a lug or projection 50 which engages the end of an arm 51 pivotally mounted on a shaft 52. The shaft 52 carries a sleeve 59 which has an arm 53 rigidly secured thereto. The outer end of arm 53 is pivotally connected to the lower end of a link rod 54, the upper end of which is pivotally connected at 55 to one end of a tape-severing knife 56. The opposite end of the tape-severing knife 56 is pivotally mounted at 57 to the framework. This mechanism is so timed and arranged that the knife 56 will sever the moistened gummed tape at about the same time that the carton has been raised to a horizontal level with the severing knife.

40

45

60

65

The continued upward movement of the shaft 44 on receiving platform 21 carries the carton 20 upwardly into a chute 60 in which is supported a pair of diametrically-opposed, vertically positioned brushes 61 and 62. These brushes contact with the carton at the points where the strip of tape lays thereacross, thus brushing down the ends of the tape snugly against the sides of the carton and sealing said tape securely thereto. Movement of the table is sufficient to raise the carton so that the lower edge thereof passes by an inwardly-turned shoulder 63 formed on a spring arm 64 carried by the chute. The shoulder 63, engaging under the

bottom of the raised carton, prevents the return of said carton when the supporting table recedes downwardly to its original lowered position. The clutch 12 is arranged to impart a single rotation only to the shaft 70 11 when engaged thereto and a suitable drag brake 65 is provided on shaft 11 for preventing the machine from overrunning.

Means are provided for discharging the sealed cartons from the top end of the chute 75 and comprise an arm 66 rigidly mounted horizontally on the top end of the vertically-disposed rocker arm 67. The lower end of arm 67 is bolted or otherwise suitably secured to a casting 68, pivotally mounted on a stud 69, rigidly secured to side frame 2. To keep the upper end of arm 67 in proper alignment with the top end of the chute 60, a guide 70 is slidably mounted thereon which rides in a guideway 71 mounted on the 85 chute 60.

Means for actuating the arm 67 comprise a cam wheel 72 keyed to shaft 11 which carries a roller 73 on one face thereof for contacting with and lifting the outer end of an arm 74, the inner end of which is keyed to a shaft 75, journaled on the side frames 1 and 2. Shaft 75 protrudes beyond the side frame 2 and has keyed thereon an upstanding arm 76, the arm 74, shaft 75, and arm 76 90 thus forming a bell-crank. The upper end of the arm 76 is pivotally connected to one end of a link 77, the other end of which is pivotally connected to the rocker arm 67.

A suitable trough or chute 78 is attached 100 to the upper end of the cylindrical chute 60 for receiving the carton 20 when moved by the arm 66.

In the operation of this machine the cartons are supplied thereto by any suitable means, such as an endless belt conveyor, and are manually placed in position on the receiving table 21 by the operator. Movement of a carton 20 onto the table 21 causes the carton to engage the upper end 19 of trigger 18 and rock the trigger to the right as viewed in Figure 2. Movement of the trigger in this manner transmits motion to the arm 16, link 15, bell-crank 14 and rod 13 to the clutch 12, causing the clutch to 110 connect the driven gear 10 to the main shaft 11.

Initial movement of the main shaft 11 causes the cam 22 to rock the link 24 to the right as shown in Figure 1. Such movement of the link 24 carries link 28 and lever 29 to the right, and thus draws the carriage 31 down the inclined guideway 32 to the position shown in full lines in Figure 1. Such movement of the carriage 31 feeds a suitable strip or length of moistened gummed tape across the top of the carton 20, so as to project a suitable distance from the opposite side thereof.

During this movement of the machine, the 130

pin 42 has been sliding down slot 41 in the upper end of the pitman 40. By the time tape has been fed into position across the top of the carton, pin 42 has reached the bottom 5 of slot 41 and continued movement of the crank 39 causes the pitman 40 to raise the shaft 44. When the shaft 44 and table 21 have been raised a short distance, preferably to bring the top of the carton 20 on a horizontal plane with the tape-severing knife 56, the lug 50 engages the arm 51 and raises 10 said arm upwardly, thus rocking the arm 53 downwardly. The downward movement of arm 53 shifts the rod 54, the upper end of which is connected at 55 to knife 56, also downwardly, causing the knife 56 to sever the length of moistened tape.

Continued upward movement of the shaft 44 and table 21 brings the carton 20 into engagement with the brushes 61 and 62, said brushes being mounted so as to wipe the protruding ends of the gummed tape down against the opposite sides of the carton 20 and thus seal the tape securely thereto. 20 When the table 21 has reached its upward limit of motion, the carton 20 has been lifted a sufficient height to permit the shoulder 63 of spring arm 64 to snap underneath the bottom side of the carton and retain it in 25 such lifted position when the table 21 recedes to its original receiving position.

During the return of the table 21 to its initial position, the roller 73 on disk wheel 72 engages the outer end of the arm 74 and 30 rocks the end of said arm upwardly. Such movement of the arm 74 rocks the shaft 75 and arm 76 in a bell-crank motion, causing the upper end of arm 76 to rock to the right as viewed in Figure 1. The link 77 which 35 connects the upper end of arm 76 to the rocker arm 67 draws said rocker arm to the right, as viewed in Figure 1, thus causing the horizontal arm 66 to push the upstanding carton, which has been raised above the 40 top end of chute 60, over onto the chute or conveyorway 78.

Although but one specific embodiment of this invention has been herein shown and described, it will be understood that details 45 of the construction shown may be altered or omitted without departing from the spirit of this invention as defined by the following claims.

I claim:

1. A machine of the class described comprising a supporting frame, a carton receiving table movably mounted on said frame, means for supplying a length of gummed tape across one side of a carton placed on said table, a chute on said frame adjacent said table for receiving said carton, means for imparting a reciprocating motion to said table for passing a carton thereon into said chute when said table moves in one direction, means on said chute for wiping

the ends of said tape against the adjacent sides of said carton when said carton moves into said chute, a source of power for operating said machine, means controlled by the placing of a carton on said table for connecting said source of power to the operated mechanism of said machine for one cycle of operation, and means for retaining said carton in such shifted position when said table returns to its initial position. 75

2. A machine of the class described comprising a supporting frame, a carton receiving table movably mounted on said frame, a trigger on said frame adjacent said receiving table in position to be shifted by a carton placed on said table, means controlled by the shifting of said trigger for supplying a length of gummed tape across the top side of said carton, the ends of said tape projecting beyond the opposite sides of said carton, a carton receiving chute on said frame in registry with and in spaced relation above said table, means for imparting a vertical reciprocating motion to said table for passing the cartons thereon into the lower end of said chute when said table is raised, yielding brushes on said chute for wiping the projecting ends of said tape against the adjacent sides of said carton when said carton moves into said chute, means for retaining said carton in such shifted position when said table moves downwardly to its initial position, and means at the top end of said chute for removing cartons when projected above the top of said chute. 90

3. A machine of the class described comprising a supporting frame, a main shaft journaled on said frame, a clutch on said shaft for connecting said shaft with a source of power, a carton receiving table movably mounted on said frame, a trigger pivoted on said frame adjacent said carton receiving table in position to be engaged and shifted by a carton placed on said table, connection between said trigger and clutch for actuating said clutch to connect said shaft with its source of power, a cam on said main shaft, means actuated by said cam for supplying a strip of gummed tape across the top side of said carton, the ends of said tape projecting beyond the opposite sides of said carton, a vertical shaft slidably mounted on said frame with the upper end thereof attached to the underside of said carton receiving table, a crank on said main shaft, a pitman connecting said crank with said table supporting shaft, a lag connection between said pitman and table supporting shaft for permitting said table to remain stationary during initial rotation of said main shaft, a knife pivoted on said frame for severing a length of said tape from a supply thereof, connections on said knife operated by upward travel of said table 100 105 110 115 120 125 130

supporting shaft for actuating said knife, a carton receiving chute on said framework located above said table and in registry therewith, brushes on said chute at diametrically opposite sides thereof for wiping the projecting ends of said tape down against the adjacent sides of said carton when said carton is moved into said chute, a spring actuated shoulder on said chute for retaining said carton in its shifted position when said table returns to its original position, a rocker arm pivoted to said framework with the upper end thereof adjacent to top end of said chute, an arm rigidly secured to upper end of said rocker arm for engaging and shifting cartons which protrude above the top end of said chute, and connections between said rocker arm and said main shaft for actuating said rocker arm at each revolution of said main shaft.

4. A machine of the class described comprising a supporting frame, a carton receiving table movably mounted on said frame, means controlled by the placing of a carton on said table for supplying a length of gummed tape across one side of said carton, a carton receiving chute having a length equal to a plurality of cartons, mounted on said frame adjacent said table, means for

imparting a reciprocating motion to said table for passing the cartons thereon into said chute when said table moves in one direction, brushes mounted on said chute and extending the length thereof for wiping the ends of said tape against the adjacent sides of said carton when said carton moves into said chute, said brushes functioning to retain the ends of said tape snugly against the sides of said carton during successive movements of said carton through said chute, and means for retaining said carton in shifted position when said table returns to its initial position.

5. A machine of the class described, comprising a frame, a chute on said frame, a carton receiving table movably mounted on said frame in registration with the interior of said chute, a one-way stop in said chute, means for reciprocating said table for successively inserting cartons into said chute above said stop and progressively moving said cartons forwardly therethrough, a platform adjacent the upper end of said chute, and a means for shifting a carton from the top of said chute onto said platform.

Signed at Chicago this 13th day of January, 1928.

WALTER L. ROGERS.
